UNITED STATES PATENT OFFICE

2,429,237

FUSE UNIT

Alric H. Powell, Yeadon, Pa., assignor to General Electric Company, a corporation of New York

Application June 29, 1944, Serial No. 542,725

11 Claims. (Cl. 200—114)

1
My invention relates to fuse units, and more particularly to fuse units employing fuses of the type disclosed and claimed in copending application Serial No. 542,726, Williams et al., filed concurrently with the present application and assigned to the same assignee as the present application.

The fuse units of my invention have many applications but they are particularly adapted for use on aircraft. At the present time the motors and controls on large aircraft have generally been supplied from a direct current source of power. It has recently been proposed to supply the electrical energy for the various motors and controls on large aircraft with alternating current of a frequency in the neighborhood of 400 cycles. The circuits for supplying this power are arranged so as to comprise numerous parallel paths each taking a more or less different course. Each of these parallel paths should be protected by a suitable circuit interrupting device. The fuse unit of my invention has been found satisfactory for such use.

It is an object of my invention to provide a new and improved fuse unit.

It is another object of my invention to provide a fuse unit which is simple and inexpensive to manufacture, and accurate and dependable in operation.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawings in which Fig. 1 is a plan view of a fuse unit embodying my invention; Fig. 2 is a sectional view taken on line 2—2 of Fig. 1 with the fuse device shown in full; Fig. 3 is a sectional view taken on line 3—3 of Fig. 1 with a portion of the handle of the fuse device cut away; Fig. 4 is a plan view partly in section similar to Fig. 1 of a modification of my invention; Fig. 5 is a sectional view taken on line 5—5 of Fig. 4; Fig. 6 is a sectional view taken on line 6—6 of Fig. 5; Fig. 7 is an end view partly in section of a fuse unit embodying still another modification of my invention; Fig. 8 is a plan view similar to Fig. 1 of still another modification of my invention; Fig. 9 is a sectional view taken on line 9—9 of Fig. 8; Fig. 10 is a sectional view taken on line 10—10 of Fig. 9 with certain parts broken away, and Fig. 11 is a sectional view similar to Fig. 10 with certain parts

broken away and with the fuse locking device out of its locking position.

Referring now to Figs. 1, 2 and 3 of my invention, there is disclosed a fuse device 1 of the type disclosed and claimed in the above mentioned Williams et al. application. This fuse device comprises a pair of molded ferrules 2 and 3 of insulating material into which a plurality of blade-like conductors 4 are molded in spaced parallel relation. Each of the blade-like conductors 4 is provided with a notched-out portion 5. A plurality of fusible elements indicated at 6 in Fig. 2 interconnect the corresponding conductors 4 associated with ferrules 2 and 3. These fusible elements extend through holes drilled longitudinally through conductors 4 and are fastened thereto by solder or the like as indicated at 7. Each fusible element is enclosed by a fuse tube 8 and the ends of the fuse tubes are adapted to fit into recesses 9 in insulating ferrules 2 and 3. Suitable fastening means such as screws 10 firmly hold the plurality of fuse tubes 8, ferrules 2 and 3 and associated conductors 4 as a unitary assembly. As is described in the above mentioned Williams et al. application, the fuse tubes 8 are filled with a granular, inert, arc quenching material which may be inserted into the fuse tubes after assembly of the fuse device through openings 11 in ferrule 3, which openings may be closed by a suitable filler plug 12 of cement or the like after the filling operation.

The ferrule 2 is provided with an integral extension 13 which serves as a handle to manually grasp the fuse device 1 for removing and inserting it with respect to an associated electrical circuit. In addition, the ferrule 2 of fuse device 1 also includes an integral extension 14 which is adapted to be engaged by cooperating locking means to be described hereinafter.

40 The fuse device 1 is adapted to cooperate with a base 15 to form the fuse unit of my invention. Supported from and suitably secured to each end of base 15 is an insulating member 16 having a plurality of barriers 17 between which are defined a plurality of recesses 18. Mounted in each recess 18 is a spring terminal clip 19 having an extension 20. A terminal screw 21 passing through an opening in the extension 20 holds each spring terminal clip 19 in position in recess 18 in insulating member 16.

45 In order that vibration will not cause the fuse device 1 to move out of contact with terminal clips 19, I provide an insulating pin 22 which passes through a plurality of the barriers 17 at one end of the base 15 so as to engage at least two

blade contacts 4, as is clearly shown in Fig. 1, whereby the corresponding end of fuse device 1 is securely held in position. In order to hold the other end of fuse device 1 in engagement with spring terminal clips 19 pivotally mounted latching member 23 is provided having integrally formed trunnions 24 adapted to be mounted in a recess in insulating member 16. A suitable spring 25 is provided with one end engaging with a notch 26 in pivotally mounted latching member 23, 10 while the other end engages with a recess 27 in insulating member 16. Spring 25 biases latching member 23 in a counter-clockwise direction as viewed in Fig. 3 so as to engage integral extension 14 of insulating ferrule 2.

To remove the fuse device 1 it is merely necessary to grasp the knurled portion 28 of latching member 23 with the thumb of one hand rotating it in a clockwise direction to the dotted position shown in Fig. 3. The handle 13 of the fuse device 1 may then be grasped with the other hand to remove the fuse device which must be moved upwardly at the end comprising the ferrule 2 so that the other end may be moved from beneath insulating pin 22.

Referring now to Figs. 4, 5 and 6, I have illustrated a modification of my invention insofar as the locking means for holding the fuse in position is concerned. The corresponding parts in Figs. 4, 5 and 6 are designated by the same reference numerals as in the preceding figures. The ferrule of insulating material for the fuse device which has been designated as 1' to distinguish it from the fuse device 1 of Fig. 1 differs from the ferrule 2 of Fig. 1 and is designated by the numeral 30. Ferrule 30 includes a handle portion 31. Reciprocatingly mounted in a recess 32 in handle 31 is a manually engageable plunger 33 which is normally biased by a spring means 34 mounted within recess 32 to assume the position indicated in Fig. 6. The manually engageable plunger 33 has a portion thereof cut away to form a cam surface 35. An inverted L-shaped member 36 suitably fastened to screw 10 as by means of a nut 37 has a portion thereof substantially perpendicular with plunger 33, with the end thereof cut off at an angle, as indicated at 38 to engage with the cam surface 35, as is clearly shown in Fig. 4. A spring member 39 also fastened to screw 10 by means of nut 37 biases inverted L-shaped member 36 into engagement with cam surface 35. It is obvious that when plunger 33 is pushed into recess 32 against the force of spring 34, that cam 35 forces inverted L-shaped member 36 to move away from the handle 31. Extending through an opening in L-shaped member 36 is a latching pin 40 which also extends through an opening 41 in handle 31. Spring 39 normally biases pin 40 in a direction so as to move toward the right, as viewed in Fig. 5. The end of pin 40 engages with a catch 42 which may be molded as an integral part of one of the barriers 17 of the insulating member designated as 16' in Fig. 4 to distinguish it from members 16 in Fig. 2. The particular barrier having integrally formed therewith the latch 42 has been designated as 17'. The insulating members 16' are secured to the base 15 by suitable means such as screws 15', one of which appears in Fig. 5.

From the above discussion it will be obvious that fuse device 1' may be removed from engagement with spring terminal clips 19 merely by grasping the handle 31 and at the same time depressing plunger 33 whereby inverted L-shaped member 36 assumes the dotted position shown

in Fig. 5 with the consequent withdrawal of pin 40 from engagement with catch 42. After the latching means is released the fuse device is removed in exactly the same manner as was discussed in connection with Figs. 1 to 3.

In Fig. 7 I have illustrated still another modification of my invention disclosed in Figs. 4, 5 and 6. The handle of the fuse device has been designated by the numeral 43. The manually depressible plunger 44, similar to the plunger 33 of Fig. 4, is reciprocably mounted in recess 45 in handle 43. A latching pin 46, similar to the latching pin 40 of Fig. 4, is provided. This latching pin, however, is arranged parallel with the plunger 44 as contrasted with the arrangement disclosed in Figs. 4, 5 and 6, where the latching plunger is arranged at right angles to the manually depressible plunger. Latching plunger 46 is reciprocably mounted in a recess 47 in handle 43 and is biased in an outward direction by spring means 48 so as to engage a catch 49 formed as a part of the insulating member 16'' which is very similar to insulating members 16 and 16' described above. The handle 43 is provided with a recess 50 into which catch 49 may move to be engaged by latching pin 46. Manually engageable plunger 44 and latching pin 46 are interconnected by a lever 51 pivotally mounted as indicated at 52 substantially at the midpoint thereof. When manually engageable plunger 44 is depressed into recess 45, lever 51 will rotate in a clockwise direction, as viewed in Fig. 7 and withdraw latching pin or plunger 46 out of engagement with catch 49 whereupon the fuse device 5 may be removed out of engagement with spring terminal clips 19 in the same manner as in Figs. 1 and 4.

Fuse units embodying my invention may be used to protect a plurality of parallel circuits. 40 In such a case it is important not only that the contact resistance at the terminals of the fuse device is low, but furthermore that the contact resistances of the parallel arranged fuse terminals are substantially equal. Otherwise the fuse device will not carry equal currents in all of its parallel paths with the possible progressive failure of the fusible elements in a multi-path fuse device. This is particularly important in connection with fuse units carrying higher currents and in Figs. 8, 9, 10 and 11 I have disclosed another embodiment of my invention including the anti-vibration locking arrangement described above combined with means for insuring very low contact resistance at each of the terminals of the multipath fuse device.

Referring now to Figs. 8 to 11, inclusive, there is disclosed a fuse unit generally indicated at 53 which is substantially identical with the fuse unit disclosed and claimed in the copending Williams et al. application referred to above. This fuse unit comprises a pair of molded ferrules 54 and 55 of insulating material into which a plurality of blade-like conductors 56 are molded in spaced parallel relationship. Each of the blade-like conductors 56 is provided with a notched-out portion 57. A plurality of fusible elements 58 and 59 shown in Figs. 10 and 11 interconnect each pair of corresponding conductors 56. These fusible elements extend through holes drilled longitudinally through conductors 56 and are fastened thereto by solder indicated at 60. Each pair of fusible elements interconnecting respective conductors 56 associated with ferrules 54 and 55 is enclosed by a fuse tube 61 and the ends of the 75 fuse tubes are adapted to fit in recesses 62 molded

in insulating ferrules 54 and 55 on the sides opposite from which conductors 56 extend. Suitable fastening means are provided to firmly hold the plurality of fuse tubes 61, ferrules 54 and 55 and the associated blade-like conductors 56 as a unitary assembly. As is described in the above mentioned Williams et al. application, the fuse tubes 61 are filled with a granular, inert, arc quenching material which may be inserted into the fuse tubes after assembly of the fuse device through openings 63 in ferrule 55, which openings may be closed by a suitable filler plug 64 of cement or the like after the filling operation.

The fuse device 53 of Figs. 8 to 11 is adapted to cooperate with a base 65 having supported from either end thereof insulating members 66 and 67, respectively, which, as shown in Fig. 9, are secured to the base by suitable means such as screws 65' indicated in dotted lines. These insulating members are provided with a plurality of barriers 68 between which are defined a plurality of recesses 69. Mounted in each recess 69 is a spring terminal clip 70, best shown in Figs. 10 and 11. These spring terminal clips are suitably fastened by means of screws 71 within each recess 69. Each spring terminal clip 70 is provided with an extension 72 and a terminal screw 73 passes through an opening in extension 72 to aid in holding the spring terminal clip in position in recess 69 and also to provide means whereby electrical connection with an associated circuit may readily be made.

In order that vibration will not cause the fuse device 53 to move out of engagement with spring terminal clips 70, I provide a locking bar 74 of insulating material which is pivotally mounted at 75 to insulating member 67. The free end of locking bar 74 is provided with an upwardly extending handle 76 which may be grasped manually to move locking bar 74 about pivot 75. Locking bar 74 is also provided with an integral extension 77 which is adapted to be engaged by a pivotally mounted latching member 78 which may be substantially identical to the latching member 23 of Figs. 1 to 3. Latching member 78 having integrally formed trunnions 79 is pivotally mounted in a recess in insulating member 66 and is biased by means of a spring 80 into latching engagement with extension 77.

In order to insure that the contact resistance between contact blades 56 and spring terminal clips 70 is very low thereby insuring uniform distribution of current between the paths of the multi-path fuse device 53 when used to protect a plurality of parallel circuits, I provide a plurality of compression springs 81. These springs 81 are arranged so that one end of a spring engages with one side of a spring terminal clip 70. The springs 81 engaging the outside terminal clips 70 of the fuse unit have the other ends thereof engaging the outside barriers 68. The intermediate springs 81 have the ends thereof which are not in engagement with contact clips 70 in engagement with an insulating spring supporting member 82. Insulating spring supporting members 82 have the upper portions thereof diverging as is clearly shown in Figs. 10 and 11, the purpose of which will become apparent hereinafter. Each insulating spring supporting member 82, as best shown in Fig. 9, has a necked-down portion 83 so that pairs of members 82 may be held in slideable arrangement in retaining members 84. Each insulating member 82, as is best shown in Fig. 11, is provided with a protrusion 85 for supporting one end of coiled compression spring 81. The 75

other end of the coiled compression spring is supported on a corresponding protrusion 86 formed integrally with the terminal clip 70. Spring terminal clips 70 and compression springs 81 are arranged so that the fuse device 53 may be readily inserted and removed without too much binding action on blade contacts 56. The position of these contacts when the locking bar 74 is out of its locking position is clearly indicated in Fig. 11. In order to reduce the contact resistance to substantially zero, locking bar 74 is provided with a plurality of extensions 87 and 88. The extensions 88 are adapted to move between the diverging portions of insulating spring supporting members 82 associated with insulating member 66 when the locking bar 74 is moved into its locking position indicated in Fig. 10, whereupon the springs 81 are compressed to insure high contact pressure. The extensions 87 move between the diverging portions of insulating spring supporting members 82 mounted in the recesses 69 in insulating member 67. The extensions 87 and 88 are tapered at the free ends thereof in order to facilitate insertion between insulating spring supporting members 82.

To remove fuse device 53 it is merely necessary to move latching member 78 out of engagement with extension 77 whereupon locking bar 74 may be rotated to the dotted position indicated in Fig. 9. Such rotation of locking bar 74 removes members 87 and 88 from between insulating spring retainers 82 (see Fig. 11) whereby the contact pressure on blade contacts 56 is greatly reduced. The fuse device 53 may then readily be removed.

It will be apparent to those skilled in the art that my invention is not limited to the particular construction shown by that changes and modifications may be made without departing from the spirit and scope of my invention, and I aim in the appended claims to cover all such changes and modifications.

What I claim as new and desire to secure by Letters Patent of the United States, is:

1. In a fuse unit, a base, a plurality of stationary contacts mounted on said base, a fuse device having a plurality of contacts for engaging said stationary contacts when said fuse device is in its current carrying position, a pair of insulating ferrules associated with said fuse device, one of said ferrules having an integral extension, and a pivotally mounted latch on said base for engaging said integral extension to prevent vibration from moving said fuse device out of position.

2. In a fuse unit, a base, a plurality of stationary contacts mounted on said base, a fuse device having a plurality of contacts for engaging said stationary contacts when said fuse device is in its current carrying position, a pair of insulating ferrules associated with said fuse device, one of said ferrules having an integral extension of insulating material, a pivotally mounted latch on said base, and spring means for biasing said latch into engagement with said integral extension to prevent vibration from moving said fuse device out of position.

3. In a fuse unit, a base, a plurality of stationary contacts mounted on said base, a fuse device having a plurality of contacts for engaging said stationary contacts when said fuse device is in its current carrying position, a pair of insulating ferrules associated with said fuse device, one of said ferrules having an extension of insulating material serving as a handle so that said fuse device may be withdrawn manually from

said stationary contacts, means for latching said fuse device into position against the effects of vibration, and manually engageable means for releasing said latching means to permit removal of said fuse device.

4. In a fuse unit, a base, a plurality of stationary contacts mounted on said base, a fuse device having a plurality of contacts for engaging said stationary contacts when said fuse device is in its current carrying position, a pair of insulating ferrules associated with said fuse device, means for latching said fuse device into position against the effects of vibration, and means for releasing said latching means.

5. In a fuse unit, a base, a plurality of stationary contacts mounted on said base, a fuse device having a plurality of contacts for engaging said stationary contacts when said fuse device is in its current carrying position, a pair of insulating ferrules associated with said fuse device, one of said ferrules having an integral extension of insulating material serving as a handle so that said fuse device may be withdrawn manually from said stationary contacts, means associated with one end of said base for holding one end of said fuse device in position against vibration or the like, and a releasable latching means for removably holding the other end of said fuse device in position.

6. In a fuse unit, a base, a plurality of stationary contact clips mounted on said base, spring means for applying contact pressure to said clips, a fuse device having contacts for engagement with said contact clips, and a member pivotally mounted on said base for holding said fuse device in position against vibration and for compressing said spring means to increase the contact pressure between said contact clips and said contacts of said fuse device.

7. In a fuse unit, a base, a plurality of stationary contact clips mounted on said base, spring means for applying contact pressure to said clips, a fuse device having blade type contacts for engagement with said contact clips, and a member pivotally mounted on said base for compressing said spring means to increase the contact pressure between said contact clips and blade type contacts.

8. In a fuse unit, a base, a plurality of stationary contacts mounted on said base, a fuse device having contacts for engagement with said stationary contacts, a member pivotally mounted on said base for holding said fuse device in current carrying position with said stationary contacts, and latching means for removably latching said member to prevent vibration from effecting said fuse device.

5. In a fuse unit, a base, a plurality of stationary contact clips mounted on said base, compression spring means for applying contact pressure to said clips, a fuse device having blade type contacts for engagement with said contact clips, a member pivotally mounted on said base for holding said fuse device in position against vibration and shock, and a plurality of extensions on said member for compressing said spring means to increase the contact pressure between said contact clips and blade type contacts.

10. In a fuse unit, a base, a plurality of stationary contacts mounted on said base, a fuse device having a plurality of contacts for engaging said stationary contacts when said fuse device is in its current carrying position, a pair of insulating ferrules associated with said fuse device, one of said ferrules having an extension of insulating material serving as a handle so that said fuse device may be withdrawn manually from said stationary contacts, means for latching said fuse device into position against the effects of vibration, and means comprising a plunger reciprocally mounted in said extension for releasing said latching means to permit removal of said fuse device.

15. In a fuse unit, a base, a plurality of stationary contacts mounted on said base, a fuse device having a plurality of contacts for engaging said stationary contacts when said fuse device is in its current carrying position, a pair of insulating ferrules associated with said fuse device, one of said ferrules having an extension of insulating material serving as a handle so that said fuse device may be withdrawn manually from said stationary contacts, means for latching said fuse device into position against the effects of vibration, means comprising a plunger reciprocally mounted in said extension, and a cam associated with said plunger for releasing said latching means to permit removal of said fuse device upon actuation of said plunger.
